UNITED STATES PATENT OFFICE.

ALEXIUS HOLMES, OF SACRAMENTO, CALIFORNIA, ASSIGNOR OF ONE-HALF
TO FREDERICK WERNER, OF SUTTERCREEK, CALIFORNIA.

PHOTOGRAPHIC-PRINTING FRAME.

SPECIFICATION forming part of Letters Patent No. 717,853, dated January 6, 1903.

Application filed January 2, 1902. Serial No. 88,082. (No model.)

To all whom it may concern:

Be it known that I, ALEXIUS HOLMES, a citizen of the United States, residing at Sacramento, county of Sacramento, State of California, have invented an Improvement in Photographic-Printing Frames; and I hereby declare the following to be a full, clear, and exact description of the same.

My invention relates to improvements in photographic apparatus, and pertains particularly to what are known as "printing-frames." Its object is to provide a frame adapted for use especially with films as distinguished from glass plates. The tendency of films to curl is well known, and the difficulty is enhanced in the case of negatives made by the so-called "panoramic" cameras, due to the proportionately greater length of the picture taken by the latter. These pictures vary in size from four by twelve to twelve by thirty-six, and it has always been a matter of considerable annoyance to hold the edges smooth and flat in the frame while placing the sensitized paper and pressure-board in place.

The invention consists of a rectangular frame, a ledge on the inner wall of the frame-opening, a pressure-board adapted to rest on said ledge and having a panel portion projecting into the space inclosed by said ledge, grooves formed in the ledge, and a slot in one end of the frame coincident with said grooves and through which a negative may be introduced into the frame.

It also comprises details of construction which will be more fully explained hereinafter.

In the accompanying drawings, Figure 1 is a sectional view taken through the line *y* *y*. Fig. 2 is a top view. Fig. 3 is a horizontal cross-section through the line *x* *x*, Fig. 1.

A represents a rectangular frame, which may be of any suitable size. A ledge *2* is formed around the four sides of the central opening, upon which the pressure-board *3* may rest. This ledge is provided with a groove or channel *4* upon three of its sides, and a slot *5* is formed in the end of the frame, which slot is continuous and in the same plane with the channels *4*. In the case of film negatives being used a suitable glass *6* is introduced into the grooves *4* through the

slot-opening *5*. This glass forms a flat support for the otherwise unstable film. The latter is then inserted through the slot and its edges engaged beneath the edges of the *55* grooves, so that it presents a smooth unrinkled surface to the pressure-board side of the frame. The sensitized paper to which it is desired to transfer the image is then placed upon the negative and the pressure-board *60* set in position and locked by means of the spring members *7* engaging the slots *8* in the opposite sides of the frame. The pressure-board *3* has a central panel portion *9* fitting the space between the walls of the *65* ledge *2*, and this panel is of sufficient depth so as to press equally and firmly on all parts of the negative, so that the sensitized printing-paper may be held properly against the negative. The accidental removal of the *70* glass or negative through the slot *5* is prevented by means of a button *10*. The holder is equally adaptable to glass-plate negatives, in which case the glass back *6* may be dispensed with. A frame so constructed is of *75* great advantage for either plates or films. In the case of the former the danger of accidental breakage by dropping from the frame through carelessness or other causes may be absolutely prevented, while in the use of *80* films there are no curled edges or corners to annoy and irritate the operator.

In the case of a great many prints being struck from the same negative the invention has the great advantage over frames of ordinary construction in that the paper may be inserted and removed with great rapidity, as the frame may be turned or held in any position without any possibility of the negative falling out. *85*

Having thus described my invention, what I claim, and desire to secure by Letters Patent, is—

1. A photographic-printing frame consisting of a rectangular frame having a channel *95* formed therein for the reception of a negative, a pressure-board, and means for holding said board in place on the frame.

2. A photographic-printing frame consisting of a rectangular frame, guides in said *100* frame for the reception of a negative whereby the latter is supported along its edges

upon its upper and lower surface, and a pressure-board fitting said frame.

3. A photographic-printing frame, consisting of a rectangular frame, a ledge on the inner wall of the opening of said frame, a pressure-board adapted to rest on said ledge, said ledge having grooves formed in it, and means by which a negative may be inserted into said grooves.

4. In a photographic-printing frame, a rectangular frame having grooves formed in the walls of the frame-opening and a slot extending through one side of the frame and coincident with said grooves, said slot and grooves adapted to receive and retain a negative.

5. A photographic-printing frame, consisting of a rectangular frame, a ledge extend-

ing around the inner walls thereof, a pressure-board adapted to rest on said ledge, said board having a central projecting panel portion extending into the space inclosed by said ledge, said ledge having grooves, and said frame having a slot in one end and in the same plane with said grooves, and means upon the frame adjacent to the slot by which a negative introduced through said slot may be prevented from accidentally being withdrawn.

In witness whereof I have hereunto set my hand.

ALEXIUS HOLMES.
